UNITED STATES PATENT OFFICE.

LOUIS SOLIGNAC, OF PARIS, FRANCE, ASSIGNOR TO THE JABLOCHKOFF ELECTRIC LIGHTING COMPANY, OF NEW YORK.

ELECTRIC CANDLE.

SPECIFICATION forming part of Letters Patent No. 257,776, dated May 9, 1882.

Application filed January 4, 1882. (No model.) Patented in France March 7, 1879, No. 129,743.

To all whom it may concern:

Be it known that I, LOUIS SOLIGNAC, of Paris, France, have invented certain new and useful Improvements in Electric Candles, of 5 which the following is a specification.

My invention relates to electric candles of the construction in which the arc is formed between two conducting sticks or pencils placed parallel to one another and separated, or surrounded, or having in association with them a mass of isolating material which is consumed with the conducting sticks or pencils, and by its incandescence adds to the size of the luminous source and improves the quality 15 of the light. This form of candle is known as the "Jablochkoff" candle. Hitherto it has been difficult to employ a continuous electric current, or one which flows constantly in the same direction with this kind of electric 20 lamp, on account of the unequal wear of the conductor sticks, pencils, or carbons.

It is well known that in electric lamps there is a transfer of material from the positive pole to the negative under the action of continuous 25 currents, so that the negative pole wears away much more slowly than the positive. Under these conditions the carbons of the Jablochkoff candle, when of the same size, wear unequally, and finally the distance between the 30 carbon points becomes so great that the candle is extinguished. This difficulty led to the employment of alternate current-generators—that is, of machines in which currents of opposite polarity or direction succeed one another. In order, however, to allow of the employment of continuous-current machines, it 35 has been proposed to make the conductor sticks or carbons of different diameter. It was found in practice, however, that the negative or 40 smaller carbon, offering too great a resistance to the current, heats, reddens, and is disaggregated, so that finally extinction results.

My invention consists in equalizing the resistance of two sticks of different size by combining with the negative or smaller carbon of the candle a wire, sheath, or core of a material (preferably a metal) that is a better conductor of electricity than the carbon. By these means the smaller or negative carbon is 45 consumed without reddening, and if the di-

ameters of the two carbons are properly proportioned they will burn evenly, like the ordinary candles, under the action of alternate currents.

My invention will be readily understood 55 from the accompanying drawings, in which Figure 1 is an elevation, and Fig. 2 a horizontal transverse section, of the candle.

a represents the negative carbon; *b*, a metallic wire embedded therein; *c*, the solid carbon of the positive pole, and *d* the isolating substance. 60

The advantages of the above improvement are as follows:

First, I am enabled to use a continuous current, instead of an alternating current, machine, thus diminishing very largely the motive power consumed. 65

Second, with equal amounts of power consumed in generating continuous currents the 70 quantity of light is much greater.

I do not limit myself to a metallic core, as it is obvious that a metallic sheath or plating may be used in its stead, or that the metallic conductor may be let into the side of the carbon. 75 Transverse sections of candles containing these modifications are shown in Figs. 3 and 4. In Fig. 3 the metallic conductor is let into the side of the carbon instead of being placed in its center. In Fig. 4 the smaller carbon is shown as having a metallic sheath. Nor do I limit myself to candles in which the positive and negative poles are of carbon, as it is obvious that the improvement does not depend upon the particular kind of stick or pencil employed. 80 85

It is also plain that my improvement is applicable to those forms of candle in which the parallel conductors are separated by an air-space, or those in which other means are used in place of the isolating substance for preventing the formation of the electric arc at any point excepting at the ends of the conductors. 90

What I claim as my invention is—

1. The combination, with two parallel conductor sticks or pencils, one of which is approximately twice the size of the other, of a wire, core, or sheath composed of a material that is a better conductor of electricity than the material of said pencils, said wire, core, or 100

sheath being applied to the smaller of the two pencils in the manner described, whereby the resistance of the two combustible sticks or pencils of different size is equalized, as and for the purpose set forth.

2. An electric candle composed of two parallel sticks of carbon separated by insulating material, one of which is approximately half

the size of the other, and is provided with a metallic conducting core, sheath, or wire, substantially as and for the purpose set forth.

LOUIS SOLIGNAC.
